REMOTELY CONTROLLED TAPE PUNCH

Henry L. Tholstrup, Rochester, N. Y., assignor to Commercial Controls Corporation, Rochester, N.Y., a corporation of Delaware

Application July 23, 1957, Serial No. 673,611

6 Claims. (Cl. 164—111)

This invention relates to tape punch structure. In its particular aspects, the invention relates to interposer control mechanism for tape punch structures.

A conventional punch used for punching combinational code holes into a tape utilizes a plurality of reciprocating punch pins, each one of which is driven from one end of a punch lever. About midway of their length, the punch levers are supported on a rotary eccentric shaft. It is characteristic of these structures that the end of the punch levers remote from their connection with the punch pin is free to rise and fall as the eccentric is rotated such that no motion is transmitted to the punch pins unless an interposer is put into the path of the remote end of the levers selected to perform a tape punching operation. Such interposers provide a fulcrum about which the eccentric can oscillate the selected punch levers to impart reciprocating movement to the punch pins controlled thereby. The invention herein relates to the foregoing type of mechanism.

It is an important object of the invention to reduce the inertia of interposer mechanism for punch structures by arranging the interposers for reciprocating movement into and out of engagement with their related punch levers.

It is a further important object of the invention to provide a positive latching mechanism by which the interposers are latched in retracted position against the bias of individual operating springs, such that upon the release of a latched interposer, it will be reciprocated into positive contact with its related punch lever.

It is still a further object of the invention to provide a latch member adapted to engage the interposer ever to latch the same in retracted position, and in conjunction therewith a bail adapted to move the interposer lever latches into interposer lever latching position and hold the latches in such position until a secure latch of the interposer levers has been effected.

It is a further object of the invention to integrate the interposer lever operation with the latch bail operation by employing a common operator for performing both of the stated functions.

It is a specific object of the invention to provide a cam device for controlling the operation of the interposer lever latch bails such that while the movement of the cam device is a continuous reciprocating movement, the control imparted by it to the bails is one of differential movement.

These and other important objects and advantages of the invention will be explained in the following description and still others will become apparent from a reading of the description in conjunction with the drawings forming a part of this application.

In the drawings:

Fig. 1 is an elevational view of a tape punch which embodies the features of the invention;

Fig. 2 is a plan view generally on the line 2—2 of Fig. 1, certain parts being removed and others being broken away to show underlying structure;

Fig. 3 is a perspective view on an enlarged scale of

2

interposer restoring bail mechanism and interposer lever latch bail operating mechanism;

Fig. 4 is a sectional view through a punch block and showing, in elevation, a punch lever and an interposer together with its control mechanism;

Fig. 5 is a diagram indicating the position of interposer lever latch bails throughout an operative cycle;

Fig. 6 is an explanatory view of a part of the control mechanism; and

Fig. 7 is a view of the mechanism represented in Fig. 6, showing, however, a different relative position of the parts.

A general understanding of the nature of the invention can be obtained by brief reference to Fig. 4, this being a view showing the punch block in section and the nature and disposition of the punch levers and their related interposers which are under control of armatures associated with selector magnets. In this figure, a punch 10 is guided through a punch block 12 over which a tape 14 passes in step-by-step progression. The punch 10 is operated by a punch lever 16 mounted on a rotary eccentric shaft 18. A guide rod 20 extends through an elongated slot in the punch lever. The punch lever 16 has a head 22 which rests in a socket in the punch 10 such that when the head 22 is oscillated by the eccentric shaft 18, the punch 10 will be reciprocated in the punch block 12 to cause code holes to be punched into the tape 14. The opposite end 24 of the punch lever 16 extends into a guide comb 26. A slot 28 in the guide comb 26 into which the end 24 of the punch lever projects is substantially deeper than the width of the punch lever end 24, thereby permitting the end 24 of the punch lever to rise and fall as the eccentric shaft 18 rotates. When the end 24 of the punch lever is unrestrained, it will rise and fall as the eccentric shaft 18 is rotated, but the punch 10 will remain at rest. In order to select a punch for operation, it is necessary to project an interposer 30 into the path of the end 24 of the punch lever. The interposer 30 blocks movement of the end 24 of the punch lever and serves as a fulcrum about which the punch lever 16 will oscillate upon continued rotation of the eccentric shaft 18. Accordingly, when an interposer 30 is engaged with the end 24 of the punch lever, the forward end 22 of the punch lever will rise and fall to reciprocate the punch 10.

The interposer is controlled by an armature 32 which is associated with an electromagnet 34. The magnet frame has attached thereto an armature pivot plate 41 provided with a pivot edge which extends just above the face of the magnet 34a where it engages a fulcrum slot 43 at the outer end of the armature 32. The armature 32, when not attracted by its magnet, is rotated outwardly about the pivot edge of the plate 41 by a coil spring 40 which is attached between the outer end of the armature and a laterally extending spring lug 45 formed at the end of the pivot plate remote from its pivot edge. The armature 32 has a notch 36 adapted to engage a lug 38 on the interposer 30. Thus, when the armature 32 is biased away from the electromagnet and the interposer 30 is drawn to its inactive position,

as shown in Fig. 4, the lug 38 of the interposer 30 will engage the slot 36 of the armature and thereby latch the interposer in its inactive position. If the magnet 34 is now energized to attract its armature 32, the latching engagement between the slot 36 and the lug 38 will be broken such that a spring 42 will project the interposer 30 toward the left in Fig. 4 where the interposer 30 blocks movement of the end 24 of the punch lever 16 to cause the punch to operate as previously stated.

Herein there are fifteen code hole punches, fifteen related interposers and control assemblies, each one being selectable for operation such that combinational codes, depending on the number of control magnets that are

energized, will be punched into the tape 14. Following each punching operation, the interposers 30 are returned to their inactive position by means of a pair of interposer restoring bails 44. Timed for operation with the movement of the interposer restoring bails 44 are a pair of armatures knock-off bails 46 and 46a which operate simultaneously to release any of the armatures 32 which are attracted to their associated magnets.

One of the important features of this invention is the control of the knock-off bails 46-46a such that they will present the armatures 32 for positive engagement of the interposer lugs 38 with their respective armature slots 36.

The disposition of the above described punch control assembly within a supporting frame is best seen in Fig. 2. The frame is generally rectangular in shape and consists of a pair of parallel side walls 48 and 48a, and a pair of parallel end walls 50 and 50a. The side walls 48 and 48a provide bearings for the eccentric shaft 18 which is adapted for rotation in conventional manner from any source of power transmitted through a conventional single revolution clutch (not shown). These side walls also provide bearings for a feed roll shaft 52.

The side wall 48a, as best shown in Fig. 1, constitutes the support for feed roll control mechanism and knock-off bail control mechanism, as will be more fully described hereinafter.

By reference to Fig. 2, it will be seen that there are seventeen punch levers associated with the punch block 12. Fifteen of these punch levers, as stated, are controlled by movable interposers in the manner previously described in connection with Fig. 4. Two of the punch levers, namely, 16a and 16b are controlled respectively by related interposers which are in permanent operating engagement therewith such that punch pins are projected by these two punch levers at each operating cycle to punch feed holes at the fourth and thirteenth punch positions respectively, as indicated at 10a and 10b of Fig. 2.

By this arrangement, it is possible to perforate four different combinations of tapes, i.e.: one fifteen code hole tape, two seven code hole tapes, two five code hole tapes, or one seven code hole tape and one five code hole tape.

The feed roller shaft 52 has a feed roller 54 mounted thereon and the latter has circumferential feed pins 54a and 54b which correspond respectively to the feed hole positions 10a and 10b. It is evident, therefore, as the tape 14 passes the punch block, the feed holes therein will be engaged by the feed pins 54a and 54b, respectively, such that the tape 14 will be advanced when the feed roller 54 is rotated.

The interposer restoring bails 44 extend through aligned slots in the opposite walls 48 and 48a of the frame where they are attached to sliding bars comprising actuators by means of which the interposer restoring bails are reciprocated.

Eccentrics 56 and 57 (Fig. 2) are mounted on opposite ends of the shaft 18. Each eccentric has a forwardly projecting finger connected to a slide bar which is guided for reciprocating movement in guide blocks and to which the opposite ends of the interposer restoring bails are attached.

In Fig. 2, the eccentrics 56 and 57 at opposite faces of the punch are mounted on the eccentric shaft 18. The forwardly projecting fingers 58 and 59 thereof are respectively pivoted to the sliding bars 62 and 63. The arrangement at opposite sides of the punch is the same such that reference to the actuator illustrated in Fig. 1 will provide an understanding of both actuators.

By reference to Fig. 1, it will be seen that the slide bar 62 extends forwardly where laterally extending flanges thereof engage a pair of guide grooves 64 and 64a in laterally spaced guide blocks 66 and 66a which are fixed to the face of the frame plate 48a. Thus, as

the eccentric 56 is operated by the eccentric shaft 18, the slide bar 62 will reciprocate in timed relation with the rotation of the eccentric shaft 18. The side plate 48a of the frame has a slot 68 formed therethrough to accommodate the interposer restoring bails 44 which are attached to the slide bar 62 such that the interposer restoring bails 44 will reciprocate with the slide bar 62.

By reference to Fig. 4, it will be seen that the interposer restoring bails overlie opposite edges of the interposers and that flanges 44a of the interposer restoring bails are adapted to engage shoulders 44b formed at the rear end of the interposers 30. Thus, as the slide bars 62 and 63 are reciprocated to the left, as shown in Fig. 2, the shoulders 44a of the interposer restoring bails will engage the shoulders 44b of the interposers and simultaneously return all interposers to an inactive position against the resistance of the interposer springs 42. The travel of the slide bars 62 and 63 and the interposer restoring bails 44 is such that the interposers 30 are carried beyond their normal latch position at which time it is intended that the knock-off bails 46 and 46a operate to present the armatures 32 so that their notches 36 can be engaged by the lugs 38 of the interposers as the interposer restoring bails begin to return and the interposers respond to the influence of the interposer springs 42.

It is a feature of the invention to so control the operation of the knock-off bails 46 and 46a that they remain in operative contact with their associated armatures and maintain the armatures in bail latching position until the interposer restoring bails 44 start to return toward the left as viewed in Fig. 4. Once the interposers are released by the interposer restoring bails 44, the interposer springs 42 will tend to project the interposers toward the left, as viewed in Fig. 4. It is necessary, therefore, that the armature knock-off bails 46 and 46a remain in operative contact with their respective armatures and hold them out until the engaging face of the interposer bail lugs 38 is in contact with the latching surface of the armature notches 36.

Reference to Fig. 3 will disclose the armature knock-off bails and the mechanism through which they are operated. The selector magnets (Fig. 4) are supported in a pair of sub-assembly frames 70 and 70a which have apertures lugs 72 (Fig. 3) by means of which these frames are fixed within the punch housing. A pair of knock-off bail operating shafts 74 and 74a extend through the side plate 48a of the housing and through the magnet frames which provide a suitable bearing for the inner ends of the operating shafts. As seen in Fig. 3, the knock-off bail operating shaft 74 is attached to one end of the knock-off bail 46, such that the bail 46 will rock as the shaft 74 is rocked. The opposite end of the knock-off bail is pivoted on a stub shaft which extends inwardly from the respective magnet frames. This arrangement can be seen in Fig. 3 wherein the knock-off bail 46 is pivoted on a stub shaft 75 which extends inwardly from the magnet frame 70. A collar such as the collar 77 may be affixed to the stub shafts when the knock-off bails have been assembled as indicated.

The ends of the shafts 74 and 74a which extend beyond the face of the frame wall 48a have attached thereto forwardly extending fingers 76 and 76a which serve as cam followers operating in conjunction with a dynamic cam arrangement by which the stated movement of the knock-off bails 46 and 46a is attained. The slide bar 62 has a cam 78 fixed to a face thereof. The contour of the cam 78 is best seen in Fig. 1, wherein it may be seen that a cam following surface 80 on the finger 76 and a similar cam following surface 80a on the finger 76a are adapted to contact opposite edges of the cam 78. When the slide bar 62 is in its retracted position, the cam followers 80 and 80a are in contact with the widest part of the cam 78 and this results in a spreading of the cam following fingers 76 and 76a and a consequent rock-

ing of the knock-off bails 46 and 46a to their outer position where they are spaced from their related armatures. However, as the slide bar 62 is reciprocated to the left, as viewed in Figs. 1 and 3, the cam followers 80 and 80a will drop into a lower position by reason of the receding contour of the cam 78. This will permit the shafts 74 and 74a to rock inwardly with the result that the knock-off bails 46 and 46a will be brought into sudden operative contact with their associated armatures thereby freeing any armature that may be stuck to its magnet due to residual magnetism and holding the related armatures in a position where they are engaged by the latch lugs 38 of the interposers.

The cam arrangement is a dynamic one by reason of a pair of sliding plates 82 and 82a which are mounted on the outer face of the slide bar 62.

Reference to Fig. 3 will show that the sliding plates 82 and 82a have elongated slots 84 extending therethrough such that when the plates are mounted on the face of the slide bar 62, as by a pair of large headed machine screws 86, the plates 82 and 82a are free to slide in reference to the cam 78 by a distance which is controlled by the length of the slots 84. The sliding plates 82 and 82a each have an upstanding stud 88 at the front end thereof which serves as an anchor for a control spring 90. One end of the control spring 90 is attached to the stud 88 while the other end is attached to an anchor stud 92 extending outwardly from the face of the slide bar 62. By reason of the spring assembly, the sliding plates 82 and 82a are normally biased toward the spring anchors 92. The front ends 94 and 94a of the sliding plates 82 and 82a, respectively, present lateral faces adapted to engage with upstanding lugs 96 and 96a, respectively, formed, respectively, on the cam following fingers 76 and 76a.

The cam followers 80 and 80a do not extend into the plane of the sliding plate surfaces 94 and 94a, respectively, while the lugs 96 and 96a are affected only by the sliding plates. The sliding plates 82-82a have downwardly stepped portions 98 and 98a, respectively, into which the upstanding lugs of the related follower fingers may drop when the position of the sliding plates in reference to the lugs is such as to permit it. In this regard, it may be noted that the follower fingers 76 and 76a are interconnected by a spring 100 which is attached to the free ends of the follower fingers such that it extends under the slide bar 62. By reason of the spring 100, the follower fingers 76 and 76a are normally biased toward each other. The wide lateral faces of the cam 78 will spread the follower fingers against the tension of the spring 100. Also, the lateral edges 94 and 94a of the sliding plates will hold the follower fingers in separated position whenever the upstanding lugs 96 and 96a of the follower fingers are in contact with the edges 94 and 94a, respectively, at the wide part of the sliding plates.

Fig. 5 of a diagrammatic illustration indicating the movement and position of the knock-off bails 46 and 46a resulting from the coaction of the cam 78 and the sliding plates 82 and 82a with the follower 80-80a and the lugs 96-96a, respectively, during a forward and return movement of the slide bar 62.

As the cam 78 moves forwardly with the slide bar 62, the sliding plates 82 and 82a tend to lag with the result that the lugs 96 and 96a remain in contact with the wider portion of the sliding plates 82 and 82a thereby maintaining the armature knock-offs in retracted position, as represented by the line *a* in Fig. 5. When the sliding plates 82 and 82a move forwardly with the slide bar 62, such that the lugs 96 and 96a drop inwardly into contact with the stepped down edges of the sliding plates 82 and 82a, respectively, the knock-off bails will be swung inwardly against the armatures, as represented by the line *b* in Fig. 5. In order to cause the knock-off bails 46 and 46a to engage and hold their respective armatures in their inner

position until a positive latching contact has been made with their respective interposer bail latch lugs, it is necessary to provide a dwell in the operation of the cam mechanism such that the knock-off bails will hold the armatures until the interposer restoring bails 44 have released the interposers and the interposers have returned to a point where their lugs engage the front end of the notch in their respective armatures. The sliding plates 82 and 82a are designed to serve this function.

- 10 Figs. 6 and 7 are explanatory figures which will clarify the function of the cam assembly. The normal rest position of the slide bar 62 is shown in Fig. 1. Herein the cam followers 80 and 80a are in contact with the wide part of the cam 78 and the lugs 96 and 96a are opposite the wide part of the sliding plates; consequently, the follower fingers 76 and 76a and their associated knock-off bails 46 and 46a are in the spread or retracted position in which the knock-off bails are spaced from their respective armatures. As the slide bar 62 moves forward into a position approximating that of Fig. 7, the cam followers 80 and 80a will be in the lower part of the cam 78 and the lugs 96 and 96a will have dropped into the stepped down portion of the sliding plates 82 and 82a, as stated. This, as stated, is the position in which the knock-off bails 46 and 46a are in contact with their respective armatures and in which the armatures are held in their position for the reception of the interposer bail latch lugs 38. The slide bar may carry the sliding plates 82 and 82a forwardly where they are free of their respective lugs 96-96a, this being the part of the movement indicated by the line *c* in Fig. 5. As the slide bar 62 begins to move back, i.e., such that the interposer restoring bails 44 release the interposers, the lugs 96-96a of the follower fingers 76 and 76a, respectively, will remain in the stepped down portion of the sliding plates 82-82a, respectively, and the shoulder at the junction of the wide and narrow section of the sliding plates will contact the respective lugs 96-96a, such that the sliding plates will be held at rest until the slide bar 62 has moved almost to the rear limit of its stroke, which is substantially the position shown in Fig. 6. Since the follower fingers 76-76a do not move laterally during this portion of the slide bar motion, there is produced a dwell in the movement of the knock-off bails 46-46a which is represented by the line *d* in Fig. 5. The line *d* is a function of the distance through which the slide bar 62 may travel in respect to the sliding plates 82-82a. After the slide bar 62 has returned to the position shown in Fig. 6, the followers 80-80a will engage the rising contour of the cam 78 such that the lugs 96-96a are withdrawn from the stepped portion of the sliding plates 82-82a, respectively. At this point, the springs 90-90a (Fig. 3) will return their respective sliding plates 82-82a to their normal position and the wide part of the cam plate 78 will rotate the knock-off bail operating shafts 74-74a into the retracted or outer position as indicated by line *e* of Fig. 5.
- It is clear, therefore, that as the slide bar 62 moves toward the right in Figs. 1 and 3, the sliding plates 82-82a will be halted momentarily by the lugs 96-96a until such time that the wide portion of the cam plate 78 separates the follower fingers 76 and 76a. It follows, therefore, that the armatures 32 are positively held in position by the knock-off bails 46 and 46a until the interposers 30 can move forward to engage the forward edge 36 of their lugs 38 in the rear wall of the armature slots 36.
- 60 The feed roll 54 (Fig. 1) is indexed by means of a feed pawl 102 which is mounted on and operated from the eccentric shaft 18. The rear end of the feed pawl 102 has a pin 104 which is adapted to slide in a slot 106 formed in a rotatable block 108. Intermediate the length of the feed pawl 102 is a tooth 110 positioned to engage the teeth of the ratchet wheel 112 fixed to the feed shaft 52. Thus, as the eccentric 18 makes a revolution, the tooth 110 is withdrawn from contact with the ratchet wheel 112, engages a succeeding tooth, and rotates the
- 70
- 75

ratchet wheel 112 to advance the tape 14 to its next punch position over the punch block 12. The ratchet wheel 112 and the feed shaft 52 are stabilized in their successive positions by a detent roller 114 which is adapted to engage the teeth of the ratchet wheel 112 at a point forward of the pawl tooth 110. The detent mechanism is mounted on a generally L-shaped plate 116 which embraces the feed shaft 52 and about which it may be adjusted. To this end the plate 116 has an elongated slot 118 adapted to receive an adjusting screw 120 which extends through the slot 118 and into an anchoring block extending outwardly from the face of the frame wall 48a. The detent roller 114 is carried at one end of a detent arm 122 such that the roller is exposed for contact with the teeth of the ratchet wheel 112. The detent arm 122 is pivoted to the plate 116 at a point 124 just below and slightly to the rear of the axis of the feed shaft 52 and it is biased in a clockwise direction about said pivot and into contact with the teeth of the ratchet wheel 112 by means of a spring 126. The spring 126 is connected between a downwardly projecting extension 128 of the plate 116 and a rearwardly located downward extension 130 of the detent plate 122.

An elongated detent actuating lever 132 has its rear end pivoted on a stud 134 that extends from the face 48a of the housing. The opposite end of the detent actuating lever 132 underlies a cam 136 on the cam shaft 18 and is provided with a cam following roller 138. Along the length of the detent actuating shaft 132 is an upstanding finger 140 which carries a laterally extending pin 142. The pin 142 extends into a slot 144 of the detent plate 122 such that it engages the wall of the slot. As a result of the relationship of the pin 142 and the wall of the slot 144, the detent plate 122 will be rocked about its pivot point 124 in a counterclockwise direction to break contact between the detent roller 114 and the teeth of the ratchet wheel 112 each time the high point of the cam 136, in engagement with the cam following roller 138, depresses the detent actuating arm 132. When the cam 136 rotates so that the high point is no longer in contact with the cam following roller 138, the spring 126 will return the detent plate 122 in a clockwise direction about its pivot 124 such that the detent roller 114 will again engage the teeth of the ratchet wheel 112. The cam 136 is so designed and positioned on the eccentric shaft 18 that the ratchet wheel 112 and the feed roll 54 are indexed one position as the punch pins are withdrawn into the punch block 12 after a punching operation.

The eccentrics on the shaft 18 are so arranged that the following sequence takes place during each punch cycle: At 49° the punch pins 10 start into the tape; the reset bails 44 engage tripped interposers at 163°; the interposers 30 release the punch lever ends 24 at 205°; the knock-off bails 36 and 46a engage their respective armatures at 227°; the detent roller 114 starts away from the ratchet wheel 112 at 244°; at 252° the interposer reset bails 44 have travelled their maximum distance to the right, as viewed in Fig. 4; the punch pins are withdrawn from the plane of the tape at 260°; at 268° the pawl tooth 110 engages the ratchet 112; at 295° the interposer restoring bails 44 begin their return movement to the left, as viewed in Fig. 4; at 296° the detent roller 114 reengages the ratchet wheel 112; the knock-off bails 46 and 46a begin to withdraw from their respective armatures at 311°; at 315° the detent roller 114 is seated between two teeth of the ratchet wheel 112; and at 349° the knock-off bails 46 and 46a have moved the maximum distance from their respective armatures.

The fact that the punch is designed for the punching of 15-code holes and two feed holes into tape which is less than 2" in width, dictates that the control magnet assembly be compactly arranged. If it is assumed that the interposers 30 are spaced from each other $\frac{1}{10}$ of an inch, it can be seen that the control magnets must be particularly arranged to accommodate them in the limited

space. Accordingly, the control magnets are provided in a pair of upper and lower rows so staggered in respect to each other that a maximum amount of space is provided for adjacent magnets of any particular row. The magnets 34a, 34b, 34c and 34d of Fig. 4 are adapted to control four adjacent interposers. Assuming that the magnet 34a is in control of the first interposer of a series of four, then magnet 34b will control the second interposer, magnet 34c will control the third interposer, and magnet 34d will control the fourth interposer of the series. By this arrangement, again assuming a distance of $\frac{1}{10}$ of an inch between interposers, there is provided a total distance of $\frac{1}{10}$ of an inch between adjacent magnets of any row.

What is claimed is:

1. Interposer mechanism for a tape punch comprising, an interposer lever mounted for movement in a fixed linear path, a latch member adapted to engage said interposer lever to latch the same against movement, a pivot for said latch member whereby said latch member may be rotated to engage and latch said interposer lever, means for rotating said latch member into interposer lever releasing position, a spring for moving said interposer lever in one direction along said path when the same is released by said latch member, reciprocating retracting means mounted for movement in a fixed path parallel to said fixed linear path for engaging and moving said interposer lever in the other direction along said path against the bias of said spring, and means under control of said retracting means for establishing and maintaining positive contact between said latch member and said interposer lever during movement of said retracting means while moving said interposer lever in said other direction.

2. Interposer mechanism for a tape punch comprising, an interposer lever mounted for movement in a fixed linear path, a latch member adapted to engage said interposer lever to latch the same against movement, a pivot for said latch member whereby said latch member may be rotated to engage and latch said interposer lever, means for rotating said latch member into interposer lever releasing position, a spring for moving said interposer lever in one direction along said path when the same is released by said latch member, reciprocating retracting means mounted for movement in a fixed path parallel to said fixed linear path for engaging and moving said interposer lever in the other direction along said path against the bias of said spring, a pivoted bail structure mounted for rocking movement into contact with and away from said latch member, and means under control of said retracting means for maintaining said bail in positive contact with said latch member while latching engagement thereof with said interposer lever is established during movement of said retracting means while moving said interposer lever in said other direction.

3. Interposer mechanism for a tape punch comprising, an interposer lever mounted for movement in a fixed linear path, a latch member adapted to engage said interposer lever to latch the same against movement, a pivot for said latch member whereby said latch member may be rotated to engage and latch said interposer lever, means for rotating said latch member into interposer lever releasing position, means for moving said interposer lever in one direction along said path when the same is released by said latch member, reciprocating retracting means for engaging and moving said interposer lever in the other direction along said path, a pivoted bail structure mounted for rocking movement into contact with and away from said latch member, a cam follower in said bail structure located along the path of said retracting means, and a cam device carried by said retracting means for engagement with said cam follower whereby said bail is rocked into contact with said latch member and is held in such contact while latching engagement thereof with said interposer lever is established during move-

ment of said retracting means while moving said interposer lever in said other direction.

4. Interposer mechanism for a tape punch comprising, an interposer lever mounted for movement in a fixed linear path, an armature adapted to engage said interposer lever to latch the same against movement, a pivot for said armature whereby said armature may be rotated to engage and latch said interposer lever, an electromagnet for rotating said latch member into interposer lever releasing position, means for moving said interposer lever in one direction along said path when the same is released by said armature, reciprocating retracting means for engaging and moving said interposer lever in the other direction along said path, a pivoted armature knock-off bail structure mounted for rocking movement into contact with and away from said armature, a cam follower in said bail structure located along the path of said retracting means, and a cam device carried by said retracting means for engagement with said cam follower whereby said bail is rocked into contact with said armature and is held in such contact while latching engagement thereof with said interposer lever is established during movement of said retracting means while moving said interposer lever in said other direction.

5. Interposer mechanism for a tape punch comprising, an interposer lever mounted for movement in a fixed linear path, a latch member adapted to engage said interposer lever to latch the same against movement, a pivot for said latch member whereby said latch member may be rotated to engage and latch said interposer lever, means for rotating said latch member into interposer lever releasing position, a spring for moving said interposer lever in one direction along said path when the same is released by said latch member, reciprocating retracting means for engaging and moving said interposer lever in the other direction along said path against the bias of said spring, a pivoted bail structure mounted for rocking movement into contact with and away from said

latch member, a cam follower in said bail structure located along the path of said retracting means, and a cam device carried by said retracting means for engagement with said cam follower whereby said bail is rocked into contact with said latch member and is held in such contact while latching engagement thereof with said interposer lever is established during movement of said retracting means while moving said interposer lever in said other direction.

- 10 6. Interposer mechanism for a tape punch comprising, an interposer lever mounted for movement in a fixed linear path, an armature adapted to engage said interposer lever to latch the same against movement, a pivot for said armature whereby said armature may be rotated to engage and latch said interposer lever, an electromagnet for rotating said latch member into interposer lever releasing position, a spring for moving said interposer lever in one direction along said path when the same is released by said armature, reciprocating retracting means for engaging and moving said interposer lever in the other direction along said path against the bias of said spring, a pivoted armature knock-off bail structure mounted for rocking movement into contact with and away from said armature, a cam follower in said bail structure located along the path of said retracting means, and a cam device carried by said retracting means for engagement with said cam follower whereby said bail is rocked into contact with said armature and is held in such contact while latching engagement thereof with said interposer lever is established during movement of said retracting means while moving said interposer lever in said other direction.
